APPARATUS FOR MEASURING LIQUIDS

Terrance O. Noble, 1416 E. 72nd St.,
Minneapolis, Minn. 55423

Filed July 18, 1973, Ser. No. 380,405

Term of patent 14 years

Int. Cl. D24—01

U.S. Cl. D32—1

FIG. 1

FIG. 2

FIG. 3

FIG. 1 is a view in perspective as seen from the front and the top of an apparatus for measuring liquids showing my new design;

FIG. 2 is a view in side elevation thereof; and FIG. 3 is a view in bottom plan thereof.

I claim:

The ornamental design for an apparatus for measuring liquids, substantially as shown.
